UNITED STATES PATENT OFFICE.

ANDREW MAGIMOREC, OF PITTSBURGH, PENNSYLVANIA.

CAR-DUMP-DOOR OPERATOR.

1,338,387.

Specification of Letters Patent.

Patented Apr. 27, 1920.

Application filed September 9, 1919. Serial No. 322,672.

To all whom it may concern:

Be it known that I, ANDREW MAGIMOREC, a citizen of Austria, and a resident of Pittsburgh, county of Allegheny and State of 5 Pennsylvania, have invented certain new and useful Improvements in Car-Dump-Door Operators, of which the following is a full and clear specification.

The object of this invention is to provide 10 a simple device for application to the chain-shaft of a dump-car door to enable the door to be opened under load-pressure without danger to the operator, the preferred construction embodying means whereby the 15 door may be opened to any degree desired and held at that point without strain upon or danger to the operator, as more fully hereinafter set forth.

In the drawing—

20 Figure 1 is a side elevation of a portion of a center-dump car showing my device applied thereto;

Figs. 2, 3 and 4 are detail views herein-after set forth.

25 The device in its preferred construction consists of a bar *a* bifurcated at one end for the reception of the worm-gear *b* whose hubs *c* are journaled in the members *d* formed by the bifurcation. Extending clear 30 through the hubs *c* and the gear *b* is a squared passage adapted to receive the squared end *e* of the usual chain-shaft of the dump-door, said shaft *e* being usually provided with a load-sustaining ratchet- 35 wheel *f* and pawl *g*.

Meshing with the worm-gear *b* is a worm *h* whose shaft *i* is journaled in the bar *a* at right angles to the axis of the worm-gear *b*. One end of this shaft extends beyond the 40 face of bar *a* and has affixed to it a ratchet-wheel *j*, and pivoted upon the extended end *k* of the shaft *i* is a hand-lever *l* which is provided with a spring-pressed pawl *m* for engagement with the ratchet-wheel *j*.

45 The application and the operation of the device will be apparent from the drawings. The wrench-like worm-gear is applied to the angular end *e* of the chain-shaft and the opposite end of the bar *a* is allowed to rest 50 in the hook-like support *n* fastened to the

car-body at a suitable distance from the chain-shaft, and then the usual load-sustaining pawl *g* is disengaged from the ratchet-wheel *f*, whereupon the weight of the load is transmitted through the medium of the 55 worm-gear *b* and worm *h* to the load-sustaining bar *a*. Then, by horizontally swinging the lever *l* back and forth, the worm-gear *h* will be rotated step-by-step to permit the weight of the load on the dump-door to open the door to the desired degree. The use of the worm-gearing makes the 60 device self-locking, so that it will not be possible for the load to suddenly dump itself when the usual pawl *g* is released. 65

A feature of importance in my device is that it may be applied to the standard dump-cars without the addition thereto of anything more than a supporting hook or lug *n*. It will be observed also that the device may 70 be used for winding up the chain for closing the door by simply removing the device from the chain-shaft and reversing it before re-applying it thereto.

I have shown in Fig. 4 an angular bushing *o* for insertion in the squared axial passage of the worm-shaft for use on chain-shafts of a small diameter, and I have also shown an extra pawl *n'* which may be brought into use by reversing the ratchet-lever *l* in case the pawl *n* is damaged enough 80 to render it inoperative.

The nature and scope of the invention having been thus indicated and its preferred embodiment having been specifically 85 described, what is claimed as new is:

1. In a device of the class set forth, a load-sustaining bar carrying a self-locking gearing for temporary engagement with the chain-shaft, and a supporting device on the 90 car for the free end of said bar.

2. In a device of the class set forth, a load-sustaining bar carrying at one end a worm-gear having an angular axial passage 95 for engagement with the end of the chain-shaft of the dump-door, a worm for operating said gearing and a lever and ratchet arrangement for operating said worm, and a supporting device on the car for the other end of said load-sustaining bar. 100

3. In a device of the class set forth, a load-sustaining bar having journaled in one end a worm-gear, said gear having a squared axial passage extending entirely through it
5 to enable the gear to be removably engaged with the squared end of the chain-shaft, of the dump-door, a worm engaging said gear and provided with a ratchet-wheel, and oscillatable ratchet-lever for operating said

ratchet-wheel, and a device on the car for 10 supporting the other end of the load-sustaining bar.

In testimony whereof I hereunto affix my signature.

ANDREW MAGIMOREC.
